(57) **CLAIM**

The ornamental design for a loading and unloading device as shown and described.

DESCRIPTION

FIG. 1 is a first perspective view of-a loading and unloading device showing my new design;

FIG. 2 is a second perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings represent portions of the loading and unloading device that form no part of the claimed design.
